UNITED STATES PATENT OFFICE.

ADOLPH P. GUSTAFSON, OF CHICAGO, ILLINOIS, ASSIGNOR TO M. SCHULZ CO., OF CHICAGO, ILLINOIS.

PNEUMATIC MOTOR.

1,325,500.

Specification of Letters Patent.

Patented Dec. 16, 1919.

Application filed May 29, 1918. Serial No. 237,221.

To all whom it may concern:

Be it known that I, ADOLPH P. GUSTAFSON, a citizen of the United States, residing at Chicago, in the county of Cook and State of Illinois, have invented a certain new and useful Improvement in Pneumatic Motors, of which the following is a full, clear, concise, and exact description, reference being had to the accompanying drawings, forming 10 a part of this specification.

My invention relates to pneumatic motors particularly adapted for use in pneumatically operated musical instruments, such for example, as player pianos.

15 One of the objects of the invention is to provide a practical and effective construction of motor having a plurality of operating bellows.

Another object of the invention is to provide a simple and advantageous construction of bellows which may be easily and simply constructed, will be durable in operation and may be readily taken apart for repair or replacement.

25 In the accompanying drawings Figure 1 is a front elevation of a pneumatic motor embodying my present invention;

Fig. 2 is a cross section on line 2—2 in Fig. 1.

30 In the drawings I show a motor having a plurality of bellows 1—1—1, and a rotary shaft 2 driven by said bellows 1 by means of cranks 3 on the shaft and connecting rods 4 between the bellows and cranks.

35 As will be seen more particularly in Fig. 2, each bellows 1 consists of two parts, an upper pneumatic 1^a and a lower pneumatic 1^b. The upper pneumatic 1^a consists of the swinging member 5 and the fixed member 6

40 with the bellows material 7 and a connecting or hinge portion 8. The lower pneumatic 1^b consists of the swinging member 9 and fixed member 10 with the hinge 11 and bellows material 12. These two pneumatics are connected together by means of a board or strip 13 which is secured to the swinging members 5 and 9 as by screws 14. The hinge 11 is of such character that swinging motion on the part of the bellows member 9 is permitted,

45 50 keeping such member 9 in the proper rela-

tive position to the fixed member 10. The hinge or connection 8 of the pneumatic 1^a is of such character as to form a loose or articulated joint or connection between the swinging member 5 and the fixed member 6. 55 Thus the swinging member 5 has a certain amount of latitude of motion which it would not have if it had a hinge such as 11 in the lower pneumatic 1^b, and consequently the lower pneumatic 1^b controls the operation of 60 the two pneumatics, 1^a and 1^b, swinging the board or strip 13 back and forth, and the loosely mounted swinging member 5 accommodates itself to the peculiar motion which will be given it by the board 13. This motion will not, of course, be the ordinary swinging motion of a loose member of a pneumatic, but instead will be not only the opening and closing movement of the member 5, but also a certain amount of longitudinal bodily movement on the part of said member 5. Thus there is perfect freedom 65 of action on the part of said member 5 and pneumatic 1^a, and no binding or holding 70 which would tend to injure or damage the pneumatic or interfere with its most efficient operation. Furthermore, the fixed member 75 80 85 90 95 100 6 of the pneumatic 1^a is preferably set down a little lower or a little farther into the supporting block of member 20 on which the pneumatics 1^a and 1^b are mounted. This gives ample room for the collapsing movement of the member 5.

It will be understood that changes and modifications may be made without departing from the spirit of the invention.

What I claim as my invention is:

1. A pneumatic motor having a pair of connected operating pneumatics, one of said pneumatics having its members hinged together and the other pneumatic having its members provided with a loose connection which permits its swinging member to adjust itself as required by the motion of the swinging member on the other pneumatic. 95

2. A pneumatic motor comprising a pair of pneumatics, the hinged ends of which are arranged end to end, one of said pneumatics having its swinging member provided with a loose connection permitting said swinging 100

member to adjust itself as required by the motion of the other swinging member.

3. A pneumatic motor comprising a pair of hinged pneumatics, with their hinged ends adjacent to one another and connected so that the swinging members of said pneumatics shall move in unison, one of said

pneumatics having its members hinged together and the other being provided with a loose connection formed by a wide piece 8 10 of cloth.

In witness whereof I hereunto subscribe my name this 1st day of April, A. D. 1918.

ADOLPH P. GUSTAFSON.
